CHRISTMAS TREE ORNAMENT

Earl W. Carlson and Gwendolyn E. Carlson, both of
312 Riverdale Drive, Glendale, Calif.

Filed July 17, 1961, Ser. No. 65,942

Term of patent 7 years

(Cl. D29—1)

FIG. 1 is a side elevational view of a Christmas tree ornament showing our new design,

FIGS. 2 and 3 are top and bottom end elevational views having reference to the position of the ornament in FIG. 1, and

FIG. 4 is a longitudinal sectional view taken on the line 4—4 of FIG. 1.

We claim:

The ornamental design for a Christmas tree ornament substantially as shown.
